[57] CLAIM

The ornamental design for an eyeglass temple screw or the like, as shown and described.

DESCRIPTION

FIG. 1 is an enlarged perspective view of an eyeglass temple screw or the like, showing my new design;
FIG. 2 is a side elevational view of the eyeglass temple screw or the like shown in FIG. 1, with the opposite side being identical except that the termination of the head slot would be at the bottom of the view;

FIG. 3 is a top plan view;

FIG. 4 is a bottom plan view.
